UNITED STATES PATENT OFFICE.

JOHN F. O'CONNOR, OF CHICAGO, ILLINOIS, ASSIGNOR TO WILLIAM H. MINER, OF CHAZY, NEW YORK.

ROLLER-BEARING.

1,372,721.

Specification of Letters Patent. Patented Mar. 29, 1921.

Application filed May 6, 1920. Serial No. 379,329.

To all whom it may concern:

Be it known that I, JOHN F. O'CONNOR, a citizen of the United States, residing at Chicago, in the county of Cook and State of Illinois, have invented a certain new and useful Improvement in Roller-Bearings, of which the following is a full, clear, concise, and exact description, reference being had to the accompanying drawings, forming a part 10 of this specification.

This invention relates to improvements in roller bearings.

One object of the invention is to provide an anti-friction roller bearing especially 15 adapted to railway cars wherein the friction is reduced substantially to a minimum and the parts made self-centering under the influence of gravity.

More specifically, the object of the invention 20 is to provide an anti-friction bearing for railway cars adapted to be mounted on one bolster and wherein is presented a roller to the opposed bolster so arranged that said roller rotates about a relatively fixed axis 25 while at the same time having a rolling bearing and also arranged as to avoid the usual disadvantages present in side bearings of the roller type having more or less delicate centering means or limited travel.

30 In the drawing forming a part of this specification, Figure 1 is a vertical sectional view through the ends of body and truck bolsters of a railway car, the improved bearing being shown in elevation as applied to the truck bolster. Fig. 2 is a vertical sectional view taken substantially on the line 2—2 of Fig. 1. Fig. 3 is a vertical sectional view of an anti-friction bearing embodying 35 my invention, the construction being somewhat different from that shown in Figs. 1 and 2. And Fig. 4 is a vertical sectional view taken substantially on the line 4—4 of Fig. 3.

40 Referring to the construction illustrated in Figs. 1 and 2, 10 denotes the under side of a body bolster of a railway car and 11 the upper part of an opposed truck bolster. The improved bearing is shown applied to the truck bolster and, as shown, comprises, 45 broadly, a retaining or base casting A; a bearing roller B; a pair of supporting rollers C—C; and frames D—D.

The base or retaining casting A is provided with suitable lugs 12—12 by which the 50 casting may be riveted or otherwise secured

to the bolster. On its interior, the casting A is provided with a curved bearing surface 13 which is symmetrically arranged with respect to the center of the casting and, in actual practice, the bearing surface 13 will 60 preferably be struck on a radius, the center of which coincides with the axis of the bearing roller B. The bearing surface 13 is formed on a web of the casting A, said web being suitably braced by vertically extending 65 ribs 14—14 formed integrally with the casting A.

The supporting rollers C—C are of like construction and are arranged to roll back and forth on the surface 13, as will be evident from an inspection of Fig. 1. Each of the rollers C has a centrally extending opening through which is inserted a removable headed pin 15, said pin 15 passing through corresponding perforations in the frames or 70 plates D, as indicated in Fig. 2. The pins 15 are held against accidental removal by cotter 16. With this construction, it is evident that the relation between the rollers C will always be maintained, their axes being held 75 at a predetermined fixed distance apart. The bearing roller B is similarly attached to the frames D by a corresponding pin 17 and cotter 18, it being noted that the axes of the pins 15 and 17 coincide with the three 80 corners of an isosceles triangle and preferably the corners of an equilateral triangle if all of the rollers C and B are of like size.

The frames or plates D, as clearly shown 85 in Fig. 1 are of triangular formation with the lower edge curved as indicated at 19 on an arc concentric with the axis of the pin 17. The plates D are positioned within triangular openings 20 formed in the upwardly extending walls 21 of the base casting A, the 90 size of the plates D being appreciably less than the size of the openings 20. The plates D are limited in their travel when the edges 22 thereof engage the corresponding edges 23 of the side walls. The side walls may be 100 slotted near the bottom of the base casting as indicated at 24 in order to facilitate clearing out of dirt or other foreign matter.

The operation of the device is as follows. When the body bolster comes into engagement with the roller B and the latter is rotated, it is evident that the rollers C will also be rotated and caused to travel in one direction up the curved bearing surface 13. During this movement, it will be noted that the 110

bearing roller B does not travel bodily but rotates about a relatively fixed axis and consequently any desired travel of the body bolster bearing surface thereon may be obtained as is customary with those types of anti-friction bearings where the anti-friction roller rotates on a fixed axle. It will also be noted that a rolling bearing or journal is provided for the bearing roller B by 10 means of the traveling rollers C—C and hence friction is reduced to a minimum since no element is required to rotate about any fixed journal or axle, the pins 15 and 17 acting merely as retainers and not as supports. 15 Upon removal of the actuating pressure, it is evident that the two rollers C—C together with the frames D will automatically return to their central normal position under the influence of gravity so that the device is self-centering and without the aid of any springs or other relatively delicate devices.

In the construction illustrated in Figs. 3 and 4, the base or retaining casting A' is of substantially the same construction as that 25 shown in the other figures except that the side walls thereof are not slotted to accommodate any triangular frames. Said casting A' is provided with an arcuate bearing surface 113 upon which are adapted to roll back 30 and forth the enlarged disk-like ends 25 of two spools C'—C', the latter having integrally formed axles 26 as indicated in Fig. 3. The spacing between the rollers or spools C'—C' is maintained by a double hook-shaped, preferably malleable casting D', the hooks 27 at the ends thereof fitting over the axles 26 as shown in Fig. 3. In this construction, the bearing roller B' is preferably provided with a tube-like journal 28 which 40 is extended beyond the ends of the roller B' and which is supported by the ends of the spools C'. A retaining pin 117 is passed through the tube journal 28 and through corresponding aligned openings in the side walls 45 121 of the base casting, said pin being held by a cotter 118.

In the construction shown in Figs. 3 and 4, and above described, the operation is substantially the same as that of the structure 50 shown in Figs. 1 and 2. In the form of Figs. 3 and 4, however, due to the reduced diameter of the journal 28, a proportionately less rotation of the spools C' will occur than will occur with the rollers C of the construction shown in Figs. 1 and 2. Stated in another manner, a rotation of the bearing roller B of the construction shown in Fig. 1, through an arc of 360° will produce a substantially equal amount of rotation of the 60 rollers C whereas, in the construction in Figs. 3 and 4, a rotation of the roller B' through an arc of 360° will produce substantially only one-half the amount of rotation of the spools C'. Hence, with the construction shown in Figs. 3 and 4, a greater

“travel” of the bearing is provided for within predetermined limits than with the construction shown in Figs. 1 and 2 where the bearing rollers are of the same size. The structure shown in Figs. 1 and 2 possesses a 70 certain advantage over that shown in Figs. 3 and 4 in that the roller B is supported throughout its entire length and hence is subjected only to compression strains whereas the roller B', or at least the journal 75 thereof is subjected to some bending moments.

Although I have herein shown and described what I now consider the preferred manner of carrying out the invention, I do 80 not wish to be limited thereto and what I claim is:

1. In an anti-friction bearing, the combination with a retaining member having a curved bearing surface symmetrically disposed with respect to the center thereof; of a pair of traveling rollers supported on said surface; means for maintaining said rollers in a predetermined relation, said pair of rollers being automatically centered under 90 the influence of gravity on said surface when the bearing is not under an actuating pressure; and a bearing roller adapted to engage an opposed bearing surface, said bearing roller having rolling bearing contact with 95 said traveling rollers.

2. In an anti-friction bearing, the combination with a retaining member having a curved bearing surface symmetrically disposed with respect to the center thereof; of 100 a pair of traveling rollers supported on said surface; means for maintaining said rollers in a predetermined relation, said pair of rollers being automatically centered under the influence of gravity on said surface when the bearing is not under an actuating pressure; and a bearing roller adapted to engage an opposed bearing surface, said bearing roller having rolling bearing contact with 105 said traveling rollers, said curved bearing surface being struck on a radius having its center coinciding with the axis of said bearing roller.

3. In an anti-friction bearing for railway cars, the combination with: a base casting 115 adapted to be secured to a truck bolster; of a bearing roller associated with said base casting and adapted to engage the bearing surface of an opposed body bolster; and traveling roller bearings mounted on the 120 base casting, arranged to support said bearing roller.

4. In a side bearing of the character described, the combination with a base casting 125 provided with an upwardly facing concave bearing surface symmetrically arranged with respect to the center of the casting; of a pair of rolling elements mounted on said bearing surface and adapted to travel back and forth thereon and center themselves un- 130

der the influence of gravity; and a bearing roller extending partly above the base casting and adapted to coöperate with an opposed bearing surface, said bearing roller 5 having rolling bearing contact with the pair of first named rolling elements.

5. In a side bearing for railway cars, the combination with a base casting adapted to be secured to a truck bolster, said casting 10 being provided with an upwardly facing concave bearing surface and spaced side walls, the latter having openings therein; of a pair of traveling rollers mounted on said

surface; a bearing roller supported by said first named pair of rollers; and frames at 15 the ends of said rollers to which the latter are attached, said frames being disposed in the openings of the side walls and maintaining a fixed relation between the three 20 rollers.

In witness that I claim the foregoing I have hereunto subscribed my name this 26th day of Apr., 1920.

JOHN F. O'CONNOR.

Witness:

CARRIE GAILING.
